UNITED STATES PATENT OFFICE.

EARL F. JAMIESON, OF BRAINERD, MINNESOTA.

PHONOGRAPH-RECORD CABINET.

Application filed November 17, 1921. Serial No. 515,922.

To all whom it may concern:

Be it known that I, EARL F. JAMIESON, a citizen of the United States, residing at Brainerd, in the county of Crow Wing and State of Minnesota, have invented certain new and useful Improvements in Phonograph-Record Cabinets; and I do declare the following to be a full, clear, and exact description of the invention, such as will enable others skilled in the art to which it applies to make and use the same.

This invention relates to an improved cabinet for holding phonograph records and one object of the invention is to provide a cabinet in which the record containing drawers or slides may be secured in a locked position only when the records are in place, movement of any one of the drawers or slides to an open position automatically causing locking of the remaining ones in a closed position.

Another object of the invention is to so construct this cabinet that with one of the drawers or slides open, the remaining slides or drawers cannot be released from a locked position until the record in use has been put back in place upon the released slide.

Another object of the invention is to provide a cabinet in which the record carrying slides or drawers may be locked in a very efficient manner and at the same time locked by means having a simple construction.

This invention is illustrated in the accompanying drawing, wherein:

Figure 1 is a horizontal sectional view through a cabinet of the improved construction.

Figure 2 is a vertical sectional view through the cabinet taken along the line 2-2 of Fig. 1 with one of the slides partially opened and the remaining slides locked.

Figure 3 is a view similar to Fig. 2 showing the slides all closed and released.

Figure 4 is a vertical sectional view through the upper portion of the cabinet with the upper slide partially opened.

Figure 5 is a fragmentary sectional view through a slide taken along the line 5-5 of Fig. 1.

This cabinet is provided with a chest or housing 1 in which will be slidably mounted the slides 2 which are slidably mounted upon supports 3. These supports 3 terminate short of the rear wall 4 of this cabinet there-

by providing space between the rear wall and the inner ends of the slides 2 and supports 3. In this space, there has been provided a plurality of vertically disposed strips or bars 5 which slidably fit into openings formed in the upper and lower walls of the cabinet. Hooks 6 extend from these bars 5 and each of the bars carries a cam finger 7. The number of vertical bars 5 correspond to the number of slides 2 and the cam fingers are so disposed upon the bars that a cam finger will extend towards each of the slides. Each of the slides carries a plate or strip 8 which extends from its rear end and is provided with an upstanding flange 9 for engagement by the hooks of the bars 5. It will thus be seen that with the slides all moved to a closed position and the bars 5 all held in a raised position, the slides may be selectively drawn outwardly, outward movement of any one of the slides permitting a bar 5 to move downwardly as shown in Fig. 2 and thus cause the hooks of this particular bar to lock the remaining slides in a closed position.

In order to permit the bars to be moved upwardly to the inoperative position, each of the slides has been provided with a T-bar 10, the shank 11 of which is slidably mounted in a groove 12 formed in the upper face of the slide and communicating with a depression 13, in which the record is to be placed. This bar 10 is provided with a finger extension 14 for engaging the finger extension 7 of the co-operating locking bar 5, and serving to retain the locking bar in a raised position. From an inspection of Figs. 1 and 5, it will be seen that the shank 11 of each of these T-bars 10 is engaged by a spring 15 which is mounted in a pocket 16 formed in the slide 2. This spring serves to normally retain the T-bar in a retracted position with the end of the shank 11 extending into the depression 13. When the disk 17 is placed in the depression, it will engage the end of the shank 11 and the T-bar will be moved to the position shown in Fig. 1. It will thus be seen that with a record in place, the finger extension 14 will extend into position for engaging the finger extension 7 of the co-operating locking bar 5 whereas with the record out of place, the finger extension 14 will not extend a sufficient amount to engage the finger extension 7. The slides can therefore only be locked against opening with

a selected slide already open and with one of the slides open, the locking mechanism cannot be moved to a releasing position without the record having been put back in the depression of the slide. It should be noted that the end of the bar 11 is true, or in other words cut away so that it can readily engage the disk record 17 and also that the depression 13 is undercut so that there will be no danger of the records being moved out of the recess when engaged with the shank 11. A finger receiving recess 18 is provided in each slide so that a record can be easily removed from the depression formed therein.

When this cabinet is in use, the records are placed in the depressions and in doing so, the bars 10 are moved outwardly against the action of the springs 15 as shown in Fig. 1. The slides will then be moved inwardly and when they are moved to the closed position, the finger 14 of each slide will engage the cam finger 7 of its co-operating locking bar 5 thus raising the locking bars and retaining them in the inoperative position so that any one of the slides may be moved outwardly. When it is desired to play a certain record, the slide carrying the desired record will be drawn outwardly. As the slide moves outwardly, the finger 14 of this slide moves from beneath the finger 7 of its co-operating bar 5 and this bar will then drop downwardly as shown in Fig. 4. The hooks 6 of this locking bar will then engage the upturned flanges 9 of the strips 8 carried by the remaining slides and the remaining slides will be securely locked against opening. After the record has been placed upon the phonograph, the slide may be pushed back into place so that it will be out of the way, but since the record is out of place, the spring 15 will hold the bar 10 in a retracted position and the finger 14 of this slide will not extend a sufficient distance to engage the cams 7 of its co-operating bar 5. It will thus be seen that although the slide can be moved to the closed position, the remaining slides will remain locked and cannot be opened while the record is out of the seat or depression 13 of this particular slide. Therefore this record will have to be put back in place before the remaining slides can be opened and there will be no danger of the records being left out of place and becoming mixed. After the record has been played, it is to be put back in the depression 13 and when put back in place, it will engage the arm 11 and move the bar 10 outwardly to the operative position. At the same time, the springs 15 will cause the arm 11 to press against the edge of the record and cause the record to be moved into the undercut portion of the depression. The record will thus be securely held in place

and will not be liable to slip out of the depression. With the record in place, the slide can then be closed and when closed its finger 14 will engage the cam finger 7 of the co-operating locking bar 5 and this locking bar will then be moved to a raised or inoperative position thus releasing all of the slides and permitting any one to be drawn out as desired.

I claim:

1. A record cabinet comprising a body, record holders movable into and out of said body, separate locking means for the holders movably mounted in said body and each having locking engagement with all but one of said holders when in a locking position, and separate releasing means for the various locking means each movably carried by one of said record holders and yieldably held out of position for engaging the co-operating locking means when an empty record holder is closed and thus permit an empty record holder to be closed without releasing the remaining record holders, a record when placed in the holder moving the releasing means carried thereby into position for engaging and moving the locking means to an inoperative position when the holder is closed.

2. A record cabinet comprising a body, record holding slides mounted in said body, vertically disposed locking bars slidably mounted in said body and each having locking engagement with all but one of said slides when in a locking position, releasing means slidably carried by each slide for moving its co-operating bar to a position for releasing the remaining slides when the said slide is closed and the releasing means in an extended position, and means yieldably retaining the releasing means in a retracted position, placing of a record upon a slide moving its releasing means to an extended position for moving its co-operating locking bar to a releasing position when the slide is closed.

3. A record cabinet comprising a body, drawers slidably mounted in said body, strips extending from the inner ends of said drawers and having upturned flanges, vertically disposed locking bars slidably mounted in said body and each having hook members for engaging the flanges of said strips and locking the drawers in a closed position, a cam carried by each of said locking bars, a T-bar upon each of said drawers having a shank extending for engagement with a record, cam engaging means carried by the T-bars and spring means for yieldably holding the T-bars moved forwardly out of position for engaging said cams and moving the locking bars to a releasing position until records are placed upon the drawers in engagement with the shanks of the T-bars.

4. A record cabinet comprising a body, record holding slides mounted in said body and having their upper faces provided with record holding recesses, each having a 5 groove leading therefrom, locking bars movably mounted in said body for engaging said slides, cross bars carried by said slides and having means for engaging the locking bars and for moving the locking bars 10 to an inoperative position, shank extensions for said cross bars fitting in said grooves, and springs engaging said shanks for yieldably holding the locking bars in a retracted inoperative position with the shanks extending into said recesses, records when 15 placed in said recesses engaging the shanks and moving the locking bars to an extended and operative position.
5. The structure of claim 4 having the springs in the form of leaf-springs secured 20 in pockets formed in the slides and extending into the grooves and engaging the shanks of the locking bars.

In testimony whereof I have hereunto set my hand.

EARL F. JAMIESON.
